(57) **CLAIM**

The ornamental design for a goal tracker container, as shown and described.

DESCRIPTION

FIG. 1 is a perspective view of a goal tracker container, showing my new design with goal tracking beads in broken lines;

FIG. 2 is a front elevational view thereof, illustrated with the goal tracking beads omitted for clarity of illustration;

FIG. 3 is a rear perspective view of FIG. 2;

FIG. 4 is a left-side elevational view of FIG. 2, the right-side elevational view being a mirror image thereof;

FIG. 5 is a top plan view of FIG. 2;

FIG. 6 is a bottom plan view of FIG. 2;

FIG. 7 is an exploded perspective view thereof, illustrated with the goal tracking beads illustrated in broken lines;

FIG. 8 is an exploded front elevational view thereof, illustrated with the goal tracking beads omitted for clarity of illustration;

FIG. 9 is an exploded rear elevational view of FIG. 8;

FIG. 10 is an exploded left-side elevational view of FIG. 8;

FIG. 11 is an exploded right-side elevational view of FIG. 8;

FIG. 12 is an exploded top plan view of FIG. 8; and,

FIG. 13 is an exploded bottom plan view of FIG. 8.

The broken lines showing goal tracking beads in FIGS. 1 and 7 depict environmental matter and form no part of the claimed design. The remaining broken lines represent portions of the goal tracker container that form no part of the claimed design.
